UNITED STATES PATENT OFFICE.

CHARLES E. PALMER, OF NEW HAVEN, CONNECTICUT.

DENTAL FILE.

SPECIFICATION forming part of Letters Patent No. 408,926, dated August 13, 1889.

Application filed May 13, 1889. Serial No. 310,623. (No model.)

To all whom it may concern:

Be it known that I, CHARLES E. PALMER, of New Haven, in the county of New Haven and State of Connecticut, have invented a new Improvement in Dental Files; and I do hereby declare the following, when taken in connection with accompanying drawings and the letters of reference marked thereon, to be a full, clear, and exact description of the same, and which said drawings constitute part of this specification, and represent, in—

Figure 1, a perspective view; Fig. 2, a transverse section on line xx of Fig. 3; Fig. 3, an edge view of the file.
15 This invention relates to an improvement in files for operating upon the teeth of horses and other animals, the object of the invention being to construct a file with a guard as an integral part thereof, and so that the said 20 guard may form substantially a continuation of the cutting-surface of the body of the file; and the invention consists in a file which in transverse section presents a flat surface, having a guard upon one edge curved into the 25 flat surface of the body of the file, the said curved surface and flat surface forming a continuous file cutting-surface, and as more fully hereinafter described.

A represents the body of the file, which is 30 preferably forged with the handle B as an integral part thereof. On one edge of the file a flange is turned at substantially right angles to the body to form the guard C. The inner surface of this guard C is curved into the 35 working-surface of the body, as seen in Fig. 2, and so that the guard and body form a continuous surface. This continuous surface of the guard and body is cut in any suitable manner for forming a file, the cutting continuing throughout the inner surface of the 40 body and guard, and so that a continuous file-working surface is produced from one edge of the body to the opposite edge and onto the

guard. The body of the file is longitudinally curved, so as to present a convex working- 45 surface, as seen in Fig. 3.

In use the file is taken in the hand in the usual manner of holding a file, the thumb resting against the guard and finger on the back of the body of the file, and so that the 50 filing or operation upon the teeth may be produced by the file cutting-surface of the guard and body, the curved surface between the guard and body giving a rounded effect upon the tooth.

The handle may be made separate from the file and attached thereto—say as by a tang, as indicated in broken lines, Fig. 1; but I prefer to make the handle as a part of the body of the file, as it is stronger and more convenient than an attached handle.

I do not claim, broadly, a file presenting an inward or concave curved surface, as such, I am aware, is not new.

I claim—

1. The herein-described dental file, consisting of a body A, with a flange C turned from one edge, the inner surface of the flange curved into the corresponding surface of the body, the said inner curved surface of the 70 flange and the body cut to form a file cutting-surface throughout, substantially as described.

2. The herein-described file, consisting of the body A, the handle B, made as an integral part thereof, the body constructed with a longitudinal flange C upon one edge, the inner surface of the said flange curved into the adjacent surface of the body, the said inner curved surface of the flange and the body 75 cut to form a continuous file cutting-surface throughout, substantially as described.

CHARLES E. PALMER.
